DESIGN FOR A CABINET FOR A SPACE HEATER OR THE LIKE

Walter C. Schneider, Lansing, Mich., assignor
to Motor Wheel Corporation, Lansing, Mich., a
corporation of Michigan

Application January 23, 1941, Serial No. 98,296

Term of patent 7 years

To all whom it may concern:

Be it known that I, Walter C. Schneider, a citizen of the United States and a resident of Lansing, in the county of Ingham and State of Michigan, have invented a new, original, and ornamental Design for a Cabinet for a Space Heater or the Like, of which the following is a specification, reference being had to the accompanying drawing, forming a part thereof.

In the drawing:

Fig. 1 is a perspective view of a cabinet for a space heater or the like embodying my new design. The grille which is only partially shown

extends throughout the areas bounded by full and/or dotted lines;

Fig. 2 is a cross sectional view on line 2—2 of Fig. 1 looking in the direction of the arrows; and

Fig. 3 is an enlarged fragmentary detail view of the grille shown in Fig. 1.

The side of the cabinet not shown is substantially like the side which is shown.

I claim:

The ornamental design for a cabinet for a space heater or the like, substantially as shown and described.

WALTER C. SCHNEIDER.
